UNITED STATES PATENT OFFICE

BERNHARDT JORGENSEN, OF BEVERLY, MASSACHUSETTS, ASSIGNOR TO UNITED SHOE MACHINERY CORPORATION, OF PATERSON, NEW JERSEY, A CORPORATION OF NEW JERSEY

LASTING MACHINE

Application filed October 15, 1927, Serial No. 226,399. Renewed December 6, 1929.

This invention relates to lasting machines for use in the manufacture of boots and shoes, and is herein illustrated as applied to a machine of the type disclosed in Letters Patent No. 1,775,225, granted upon an earlier application of mine on Sept. 9, 1930, for lasting shoes of that kind in which the upper is fastened to the insole in the lasting operation by cement, for example shoes commonly known as tennis shoes. It is to be understood, however, that the invention is not limited to the lasting of shoes of that particular type nor to a machine organization of that particular character.

In the lasting of shoes in which the insole is comparatively soft and pliable, such as tennis shoes, it is important to control the insole in such manner that no portion of it will be wrinkled or otherwise displaced by the laying or wiping of the margin of the upper inwardly over it. The present invention, in one of its important aspects, provides novel means for guarding against such displacement of an insole in the lasting operation. In the illustrative application of the invention to means for lasting the toe portion of a shoe by the use of wipers, there are provided members for engaging the marginal portion of the insole at the opposite sides of the toe to press the insole upon the bottom of the last, these members comprising rolls which are yieldingly movable in directions away from the bottom face of the insole in response to the inward movement of the wipers, to permit the margin of the upper to be wiped inwardly between said members and the insole, and are also rotatable to facilitate the inward wiping action of the wipers. As herein illustrated, the rolls are arranged to act also as "retarders" to increase the effective wiping pressure of the wipers on the upper by engaging the margin of the upper and bending it outwardly over the edges of the wipers, the rolls being turned by the frictional contact of the upper therewith so that any possibility of undue strain on the upper is avoided. In the organization herein shown, moreover, the insole-controlling rolls are combined with means of the character disclosed in the Letters Pat-

ent above mentioned for controlling the margin of the insole about the end portion of the toe, and with lasting straps arranged to lay the margin of the upper over the insole at the rear side portions of the toe in accordance with the disclosure of other Letters Patent No. 1,778,192, granted upon an application of mine on Oct. 14, 1930, the rolls being arranged to operate in the intervals between said controlling means and lasting straps.

In a further aspect the invention provides novel means for insuring a proper co-operative relation between end-lasting mechanism and means for applying pressure to the bottom of a shoe in any position of adjustment of the lasting mechanism for different sizes of shoes. In machines of the type illustrated the toe-lasting mechanism is mounted for adjustment lengthwise of the shoe, and in cooperation with the lasting mechanism there is provided a presser foot for engaging the toe end of the insole to assist in controlling the insole and to depress the shoe relatively to the lasting mechanism; and as applied to such an organization the invention provides connections for adjusting the presser foot lengthwise of the shoe simultaneously with the toe-lasting mechanism. As herein illustrated, the presser foot has associated therewith, for simultaneous adjustment lengthwise of the shoe, means of the character hereinbefore described for also controlling the marginal portion of the insole, and by the adjusting connections provided insurance is therefore afforded of a proper co-operative relation between the different insole-controlling devices and the toe end of the insole of each size of shoe in accordance with the adjustment of the toe-lasting mechanism for that size of shoe.

The above and other features of the invention, including various details of construction and combinations of parts, will now be more particularly described by reference to the accompanying drawings and thereafter pointed out in the claims.

In the drawings,

Fig. 1 is a view in front elevation of one end portion of a machine of the same gen-

eral character as disclosed in the above-mentioned Letters Patent, with the present invention embodied therein;

Fig. 2 is a right-hand side elevation of 5 portions of the structure shown in Fig. 1, with a shoe shown in section to illustrate the relation of the insole-controlling rolls to the shoe and the wipers;

Fig. 3 is a plan view further illustrating 10 the action of the insole-controlling devices on a shoe; and

Fig. 4 is a view in right-hand side elevation, with parts in section, illustrating more 15 fully the adjusting connections between the toe-lasting mechanism and the toe presser foot arm.

Since the general organization and manner 20 of operation of the type of machine illustrated are fully disclosed in the earlier Letters Patent, only such parts of the machine as it is necessary to refer to for an understanding of the present invention will be 25 described in detail. It will be understood that a last having an upper *a* and an insole *b* thereon is mounted upon a heel end support (not shown) with the toe end of the shoe positioned upon a toe rest 10 which is depressible with the shoe against the resistance of a spring 12 mounted in a holder 14 which is 30 supported by a slide 18 mounted for movement lengthwise of the shoe along guideways on the frame. The slide 18 has also mounted thereon for adjusting movement about an axis extending widthwise of the shoe a casing 35 22 which supports toe-lasting wipers comprising a pair of curved wiper plates 24 (Fig. 3) for wiping the upper inwardly over the insole about the end portion of the toe and additional wiper plates 26 which are arranged 40 to act at the sides of the toe beyond the ends of the plates 24, as fully described in the earlier Letters Patent. It will be understood that the wiper plates 24 having advancing movements lengthwise of the shoe and 45 closing movements laterally of the shoe, while the plates 26 are mounted for movements only in directions laterally of the shoe, being provided with thin wiping edges which underlie portions of the plates 24. As fully 50 disclosed also in Letters Patent No. 1,778,192, the side wiper plates 26 are connected at their rear ends to flexible lasting straps 28 through which these plates act to lay portions of the margin of the upper inwardly over the 55 insole without any substantial wiping action thereon, these straps being arranged to begin their overlaying action on the upper slightly in advance of the inward wiping action of the plates 26 in front of the straps, as illustrated in Fig. 3.

For depressing the shoe relatively to the lasting means and for thereby effecting an up-wiping operation upon the upper around the toe and the positioning of the toe end of 60 the shoe in proper relation for the wipers 24,

26 to wipe the upper inwardly over the insole, as more fully disclosed in the earlier Letters Patent, there is provided mechanism including a toe presser foot 30 which engages the intermediate portion of the toe end of the insole, this presser foot being adjustably mounted, as hereinafter described, upon a supporting arm 32 movable lengthwise in a horizontal plane in a holder 34 secured to a post 36 which is mounted for vertical movement and also for turning movement in bearings in the frame of the machine. As disclosed in Letters Patent No. 1,775,225, the post 36 is normally elevated and turned so as to position the presser foot 30 above and at the rear of the location of the shoe, and by turning movement and downward movement of the post in the operation of the machine the presser foot is swung forwardly to a position over the shoe and is carried downwardly to engage the insole and depress the shoe.

As also disclosed in the earlier Letters Patent, the machine is further provided with means for controlling the margin of the insole around the end portion of the toe and for assisting the wipers in wiping the margin of the upper tightly inward over the insole, comprising a member 38 which engages the insole and acts as a retarder on the upper. This member is curved similarly to the edge of the toe end of the insole and is supported upon the presser foot-carrying arm 32 by means of an arm 40 and links 42 and 44. The arm 40 is pivotally connected at 46 to the member 38 to permit this member to adjust itself to the lengthwise contour of the shoe bottom. The links 42 and 44 are pivotally connected to the arm 40 at their lower ends and at their upper ends are pivotally connected respectively to the arm 32 and to a plunger 48 which is mounted for vertical movement in the arm 32 against the resistance of a spring 50. A spring 52 connecting the link 42 to the arm 32 tends to position the parts as shown in Fig. 1, while permitting the arm 40 to be swung by the links 42, 44 to carry the member 38 forwardly toward the end of the toe. For imparting such forward movement to the member 38 there is connected to the link 42 a gear sector 54 engaged by a vertically movable rack bar 56 which is mounted in the arm 32 with its lower end projecting downwardly below the arm. In the construction herein shown there is provided for engagement with an adjustable screw 57 on the lower end of the rack bar 56 a plate 58 secured to a bracket 60 fast on the frame of the machine. When the arm 32 receives its downward movement to carry the presser foot 30 into engagement with the insole and to depress the shoe, the rack bar 56, by the engagement of the screw 57 with the plate 58, causes the arm 40 and the member 38 to be moved forwardly over the shoe to carry the member 38 nearer to the edge of the 130

5 insole and nearer to the wipers, so that this member is positioned close to the edge of the insole to hold the margin of the insole upon the bottom of the last as the wipers begin to wipe the upper inwardly, while at the same time bending the margin of the upper outwardly over the wipers to increase their wiping pressure on the upper. It will be understood that the member 38 can yield bodily 10 upward from the bottom face of the insole against the resistance of the spring 50, and by reason of the outwardly flared shape of its upper-engaging face it is thus wedged upwardly by the wipers in the wiping operation to permit the margin of the upper to be wiped inwardly between this member and the insole.

15 The presser foot 30, in the construction herein shown, is pivoted at 62 on a bracket 20 64 which is vertically adjustable in a guide-way formed in the end of the arm 32 to permit a variation of the height of the presser foot relatively to the arm 32 and thus to determine, as desired, the plane in which the bottom face 25 of the toe end of the insole is presented for the action of the wipers. For adjusting the bracket 64 there is provided an arm 66 connected to an eccentric 68 mounted in a slot formed in a portion of the bracket 64, and for maintaining the parts in various positions 30 of adjustment there are provided in the arm 32 a series of holes 70 arranged to receive a pin 72 carried by the arm 66.

35 The present invention, in its illustrated embodiment, provides means for controlling the marginal portion of the insole at the opposite sides of the toe between the rear end of the member 38 and the lasting straps 28. For this purpose the presser foot member 30 is provided with a pivot stud 74 upon which are pivotally mounted a pair of arms 76 extending outwardly toward the opposite sides of the shoe and each having on its outer end a pair of rolls 78 for engaging the insole near 40 its marginal edge. A spring 80 the opposite ends of which are mounted in sockets formed in the arms 76 tends to swing the rolls downwardly while permitting them to yield upwardly in directions away from the bottom 45 face of the insole. When the parts are in their idle positions, the arms 76 are in engagement with the presser foot 30 to limit downward swinging movement of the rolls, the latter being then so positioned that they 50 extend downward somewhat below the lower face of the presser foot, as illustrated in Fig. 1, so that when the presser foot is carried downwardly into engagement with the insole the rolls will engage the opposite side 55 portions of the insole under spring pressure. The rolls 78 are thus so arranged as to afford additional insurance that portions of the margin of the insole between the member 38 and the lasting straps 28 will not be displaced by the 60 inward wiping action of the wipers 26. As

the wipers continue their inward movement after bending the margin of the upper inwardly over the extreme outer edge of the insole, the rolls 78 yield upwardly against the resistance of the spring 80 in response to the wedging action of the wipers thereon, thus permitting the upper to be wiped inwardly between the rolls and the insole, as will be evident by reference to Fig. 2. It will be further evident that the rolls 78 act additionally 70 to bend the margin of the upper outwardly over the edges of the wipers and thus serve as retarders in the same general manner as the member 38. The provision for turning movement of the rolls 78 on the arms 76 in response to frictional engagement of the upper or the wipers therewith facilitates the inward wiping action of the wipers and also avoids any possibility of undue strain on the upper in the locations where the rolls are positioned. 75

80 As hereinbefore described, the toe-lasting mechanism including the supporting slide 18 is mounted for adjusting movement on the frame of the machine in directions lengthwise of the shoe to adapt the machine to operate on shoes of different lengths. For thus adjusting the lasting mechanism there is provided a screw 82, Fig. 1, which may be operated by a hand-wheel (not shown), as described in Letters Patent No. 1,775,225. As 85 the toe-lasting mechanism is thus adjusted for shoes of different lengths, the presser foot 30 and the parts associated therewith, comprising the member 38 and the rolls 78, should also be adjusted in directions lengthwise of the shoe to operate properly on each size of shoe. The invention further provides means for insuring a proper co-operative relation between the toe-lasting mechanism or wipers and the insole-engaging means, without requiring any special attention on the operator's part, by connecting the arm 32 to the toe-lasting mechanism so that the arm is adjusted simultaneously with said mechanism 90 through the action of the screw 82. For this purpose there is connected to the slide 18 a rack bar 84 which engages a pinion 86 on a shaft 88 mounted in a stationary bearing on the frame, this shaft being connected at 90 by a universal joint with a member 92 of a telescopic shaft. The other member 94 of this telescopic shaft is mounted to slide lengthwise of the member 92 and is connected by a universal joint at 96 to a shaft 98 mounted in bearings in the holder 34 on the post 36. 95 Fast on the shaft 98 is a pinion 100 which is connected through a second pinion 102 to a rack bar 104 fast on the arm 32. It will thus be seen that as the toe-lasting mechanism receives its adjusting movement lengthwise of the shoe, the arm 32 also is adjusted lengthwise through the connections described to maintain the presser foot 30 and the other parts carried by the arm in proper relation 100 to the toe-lasting mechanism to act in the 105 110 115 120 125 130

required manner on each size of shoe. It will be evident that by reason of the character of the connections, including the telescopic shaft 92, 94 and the universal joints 90 and 96, the adjustment of the arm 32 is not affected by the vertical movements of the post 36 in the operation of the machine.

The manner of operation of the mechanisms provided by this invention having been sufficiently pointed out in connection with the description of these mechanisms, no further explanation is required.

Having described the invention, what I claim as new and desire to secure by Letters Patent of the United States is:—

1. In a machine of the class described, the combination with means for laying the margin of an upper inwardly over an insole on a last, of a roll arranged to engage the insole near its marginal edge to hold the margin of the insole upon the bottom of the last, said roll being yieldingly movable in a direction away from the bottom face of the insole and also rotatable in response to the inward movement of the overlaying means to permit and facilitate laying of the margin of the upper inwardly between the roll and the insole.

2. In a machine of the class described, the combination with a wiper for wiping the margin of an upper inwardly over an insole on a last, of a roll arranged to engage the insole near its marginal edge to hold the margin of the insole upon the bottom of the last, said roll being arranged to act as a retarder in engagement with the margin of the upper to increase the pressure of the wiper on the upper and being so mounted as to be moved away from the bottom face of the insole and also turned by the inward movement of the wiper to permit the margin of the upper to be wiped inwardly between the roll and the insole without undue strain on the upper.

3. In a machine of the class described, the combination with means for laying the margin of an upper inwardly over an insole on a last about an end of the last, of means for engaging the marginal portion of the insole at the opposite sides of the end of the last to hold the insole on the bottom of the last comprising members mounted for movements independently at the opposite sides in directions away from the bottom face of the insole in response to the inward movement of the overlaying means to permit the margin of the upper to be laid inwardly between said members and the insole.

4. In a machine of the class described, the combination with wipers for wiping the margin of an upper inwardly over an insole on a last about an end of the last, of rolls arranged to engage the margin of the insole at opposite sides of the end of the last to hold

the insole upon the bottom of the last, said rolls being yieldingly movable in directions away from the bottom face of the insole and also rotatable in response to the inward movement of the wipers to permit and facilitate wiping of the margin of the upper inwardly between said rolls and the insole.

5. In a machine of the class described, the combination with wipers for wiping the margin of an upper inwardly over an insole on a last about an end of the last, of a presser foot arranged to engage the intermediate portion of the end of the insole, a support for said presser foot, and members carried by said support for engaging the marginal portion of the insole at its opposite sides to hold the margin of the insole upon the bottom of the last, said members being yieldingly movable independently at the opposite sides in directions away from the bottom face of the insole in response to the inward movement of the wipers to permit the margin of the upper to be wiped inwardly between said members and the insole.

6. In a machine of the class described, the combination with wipers for wiping the margin of an upper inwardly over an insole on a last about an end of the last, of a presser foot arranged to engage the intermediate portion of the end of the insole, a support for said presser foot, pivotally mounted arms carried by said support and extending outwardly toward the opposite side edges of the insole, rolls carried by said arms for engaging the margin of the insole to hold it upon the bottom of the last, and spring means acting on said arms to press the rolls upon the insole and yieldable in response to the inward movement of the wipers to permit the margin of the upper to be wiped inwardly between the rolls and the insole.

7. In a machine of the class described, the combination with wipers for wiping the margin of an upper inwardly over an insole about the toe end of a last, of a member arranged to engage the margin of the insole about the end portion of the toe to hold the insole on the bottom of the last and to be displaced by the inward movement of the wipers, and additional members for engaging the margin of the insole at the opposite sides of the toe at the rear of said first-named member to hold the margin of the insole on the bottom of the last, said additional members being yieldingly movable in directions away from the bottom face of the insole in response to the inward movement of the wipers to permit the margin of the upper to be wiped inwardly between said members and the insole.

8. In a machine of the class described, the combination with wipers for wiping the margin of an upper inwardly over an insole about

the toe end of a last, of a curved member arranged to engage the margin of the insole about the end portion of the toe and movable forwardly to spread the margin of the upper 5 outwardly over the wipers, said member being yieldingly movable also in a direction away from the bottom face of the insole in response to the inward movement of the wipers, and rolls arranged to engage the margin 10 of the insole at the opposite sides of the toe at the rear of said curved member to hold the margin of the insole upon the bottom of the last, said rolls being yieldingly movable in directions away from the bottom face of the 15 insole and also rotatable in response to the inward movement of the wipers.

9. In a machine of the class described, the combination with wipers for wiping the margin of an upper inwardly over an insole 20 about the toe end of a last, of a presser foot arranged to engage the intermediate portion of the toe end of the insole, a support for said presser foot, a member carried by said support for engaging the margin of the insole about the end portion of the toe to hold the insole on the bottom of the last and yieldable in a direction away from the bottom face of the insole in response to the inward movement of the wipers, and rolls carried by 25 said support for engaging the margin of the insole at the opposite sides of the toe at the rear of said member, said rolls being yieldingly movable in directions away from the bottom face of the insole and also rotatable 30 in response to the inward movement of the wipers.

10. In a machine of the class described, the combination with wipers for wiping the margin of an upper inwardly over an insole 40 about the toe end of a last, of insole-positioning means arranged to engage the margin of the insole about the end portion of the toe to hold the insole upon the bottom of the last and yieldingly movable in a direction away from the bottom face of the insole in response to the inward movement of the wipers, flexible lasting straps arranged to be operated by the wipers to lay the margin of the upper inwardly over the insole in locations 45 spaced rearwardly from said insole-positioning means, and members arranged to engage the margin of the insole between said positioning means and lasting straps to hold the margin of the insole upon the bottom of the 50 last in those locations, said members being yieldingly movable in directions away from the bottom face of the insole in response to the inward movement of the wipers to permit the margin of the upper to be wiped inwardly 55 between said members and the insole.

11. In a machine of the class described, the combination with wipers for wiping the margin of an upper inwardly over an insole about the toe end of a last, of a presser foot arranged 60 to engage the intermediate portion of the toe

end of the insole, a support for said presser foot, a member carried by said support for engaging the margin of the insole about the end portion of the toe to hold the insole upon the bottom of the last, said member being 70 movable forwardly toward the toe end of the insole while engaging the insole and being yieldingly movable in a direction away from the bottom face of the insole in response to the inward movement of the wipers, flexible 75 lasting straps arranged to be operated by the rear end portions of the wipers to lay the margin of the upper over the insole, and rolls carried by said presser foot support for engaging the margin of the insole at its opposite sides to hold it upon the bottom of the last in locations between said forwardly movable member and the lasting straps, said rolls being yieldingly movable away from the bottom face of the insole in response to the inward movement of the wipers. 80

12. In a machine of the class described, the combination with shoe-positioning means, of end-lasting mechanism adjustably movable lengthwise of the shoe, a presser foot mounted independently of said end-lasting mechanism for engaging the bottom of the shoe, and connections between said presser foot and the end-lasting mechanism for adjusting said presser foot lengthwise of the shoe with said 90 mechanism.

13. In a machine of the class described, the combination with means for positioning a last having an upper and an insole thereon, of toe-lasting mechanism, means for adjusting said toe-lasting mechanism lengthwise of the last, a presser foot mounted independently of said toe-lasting mechanism for engaging the toe end of the insole, and mechanism connecting said adjusting means to the presser foot for adjusting the presser foot simultaneously with the toe-lasting mechanism. 100

14. In a machine of the class described, the combination with means for positioning a last having an upper and an insole thereon, of toe-lasting mechanism comprising wipers for wiping the margin of the upper about the toe inwardly over the insole, means for adjusting said toe-lasting mechanism lengthwise of the shoe, means mounted independently of said toe-lasting mechanism for engaging the margin of the insole at the toe end to control it in the lasting operation, and connections between said insole-controlling means and the adjusting means for the toe-lasting mechanism for adjusting said controlling means with said mechanism. 110

15. In a machine of the class described, the combination with means for positioning a last having an upper and an insole thereon, of toe-lasting mechanism adjustable lengthwise of the last to operate upon shoes of different sizes, a device for engaging the toe end of the insole mounted independently of the toe- 125 130

lasting mechanism for movement into and out of position over the last and also for movement into and out of engagement with the insole, and means connecting said insole-engaging device to the toe-lasting mechanism for adjusting said device lengthwise of the shoe with said mechanism.

16. In a machine of the class described, the combination with shoe-positioning means, of end-lasting mechanism movable lengthwise of the shoe, a device mounted independently of said end-lasting mechanism for engaging the bottom of the shoe to control it in the lasting operation, and means comprising gearing connecting said device and the end-lasting mechanism for simultaneous movement when said mechanism is moved.

17. In a machine of the class described, the combination with a wiper for laying the margin of an upper inwardly over an insole, of a member arranged to engage the insole in the path of movement of the wiper and also to engage the margin of the upper and bend it outwardly over the edge of the wiper as the upper is being wiped inwardly, said member being movable away from the insole in response to wedging action of the wiper thereon and also rotatable through frictional contact of the margin of the upper therewith.

18. In a machine of the class described, the combination with wipers for laying the margin of an upper inwardly over an insole about an end of the insole, of members arranged to engage the insole near its opposite side edges in the path of movement of the wipers and also to engage the margin of the upper and bend it outwardly over the edges of the wipers as the upper is being wiped inwardly, and means for yieldingly pressing said members upon the insole with provision for their movement away from the insole in response to wedging action of the wipers thereon, said members being so mounted as to be turned by the frictional contact of the margin of the upper therewith.

In testimony whereof I have signed my name to this specification.

BERNHARDT JORGENSEN.
